DESCRIPTION

The FIGURE is a face view of a display screen including icons showing the design.

icons showing the design. The outermost broken lines in an equal length dash pattern illustrate an unclaimed bezel of a display device including the display screen and form no part of the claimed design. The broken lines in a long-long-short dash pattern are boundary lines that illustrate the display screen and form no part of the claimed design. The remaining dotted broken lines illustrate portions of a graphical user interface that forms no part of the claimed design.
